UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed November 12, 1923. Serial No. 674,189.

To all whom it may concern:

Be it known that I, EDWARD S. STIMPSON, a citizen of the United States, residing at Hopedale, in the county of Worcester and 5 State of Massachusetts, have invented an Improvement in Feeler Mechanisms for Looms, of which the following description, in connection with the accompanying drawings, is a specification, like characters on 10 the drawings representing like parts.

This invention relates to feeler mechanisms for looms, whereby the filling is replenished from time to time prior to complete exhaustion.

15 Various kinds of feeler mechanisms have heretofore been suggested for the purpose of either stopping the loom or replenishing the filling when the filling in the shuttle has reached a degree of substantial exhaustion, 20 and it is now the common practice to provide the feeler mechanism with a feeler which enters the shuttle on each detecting beat and contacts with the filling, and when the filling becomes substantially exhausted the feeler 25 detects this condition and sets in operation a train of mechanism for replenishing the filling.

30 This constantly recurring contact of the feeler with the filling on each detecting beat is liable to injure the filling, especially when the filling is of fine count or is formed of material that is readily damaged. Since the function of the feeler is to call for a change 35 of filling when that in the shuttle has become substantially exhausted it is sufficient if the feeler performs its feeling function when the filling has approached the danger point, and initiates replenishment of filling when that in the shuttle has become substantially exhausted.

40 Therefore, one of the objects of the present invention is to provide a feeler mechanism for looms with means for holding the feeler in a retracted or inoperative position 45 with respect to the filling for periods of time and for rendering the feeler operative to engage the filling only at intervals, until it detects a near approach to substantial exhaustion of the filling, whereupon the feeler 50 may remain operative and upon detection of substantial exhaustion of filling, set in operation a train of mechanism to replenish the filling.

In carrying out this object of the inven-

tion, the feeler upon a detecting beat enters 55 the shuttle to engage the filling therein, and if a working supply of filling is present the feeler is pushed forward as the lay beats up, and means is provided for engaging the feeler when it is pushed forward and for 60 holding the feeler in the retracted position for a period of time.

When the feeler is in its retracted position it is desirable that the same be held in a position in which it will be entirely out of engagement of the filling on a detecting beat, and an important feature of the present invention therefore resides in simple means 65 for imparting an additional forward movement to the feeler to hold the same in 70 a forward position beyond that to which it is pushed by a working supply of filling on a detecting beat, whereby the feeler is held entirely out of reach of the filling.

75 Another feature of the invention resides in novel means for automatically releasing the feeler after it has been held inactive for a period of time, and still another feature of the invention resides in means for accurately adjusting the feeler holding means 80 to the desired position.

85 Other features of the invention and novel combination of parts in addition to the above will be hereinafter described in connection with the accompanying drawings which 90 illustrate one good practical form thereof.

In the drawings:

95 Fig. 1 is a perspective view of one side of the loom equipped with a feeler mechanism embodying the present invention;

Fig. 2 is an enlarged perspective view of the feeler mechanism showing the feeler held in its retracted position;

Fig. 3 is an end view of Fig. 2 with parts in section;

Fig. 4 is a plan view of the front portion of Fig. 2;

Fig. 5 is a perspective view of a modification in the construction of the detent for holding the feeler in the inoperative position;

Fig. 6 is an enlarged transverse sectional view through the bracket of Fig. 5; and

Fig. 7 is an enlarged side view of the detent releasing means.

100 The present invention will be described in connection with a feeler mechanism in which the feeler is of the inclined type and enters 105

the shuttle in a direction inclined to the longitudinal axis of the shuttle, but it will be understood that the present invention is not restricted to this type of feeler and that it may be employed in connection with other types of feelers.

The loom frame 1 may be of usual construction comprising the side frames 2 and breast beam 3 on which is secured at either side of the loom a bracket 4 having bearings for the usual transverse or rock shaft 5 which is operatively in control of the replenishing mechanism. It has not been deemed necessary to show and describe the details of the replenishing mechanism because such mechanism may be of any of the well-known types now in common use and the details thereof form no part of the present invention.

Secured to the rock shaft 5 and extending upwardly therefrom is the arm 6 to which is pivotally connected at 7 a rearwardly extending arm 8, the rear end portion of which is adapted to be engaged at times with an operating member 9 which may be formed as part of or associated with the cam follower. In the present instance, the arm 8 has pivotally connected to it at 10 a rearwardly extending end portion 11 which is normally out of the path of movement of the operating member 9, and connected to the part 11 is a lug 12 overlying the horizontal arm 13 of a bell crank lever pivoted at 14 to a support 15 secured at 16 to the loom frame. The downwardly extending arm 17 of the bell crank lever is connected to a transmitter 18 which is operatively connected at its other end to a slide 19 under the control of the feeler.

Extending from the loom frame is the shipper stand 20 to which is adjustably connected the feeler stand 21 by means of the bolt or set screw 22, as usual.

The feeler 23, as hereinbefore noted, is shown as of the inclined type and is supported upon the feeler stand 21 for movement towards and from the front of the loom. The feeler 23 passes through the bearings at the rear of the feeler stand and also through an opening in the slide 19 which is guided for lateral movement at the rear of the feeler stand, and forward of the rear bearing or guide for the slide the feeler is provided with a bridge or support 24 to which the feeler is secured. Extending forwardly from the bridge 24 is the feeler stem 25 which passes through the swivel block 26 mounted on the feeler stand by means of a bracket 27, and between the swivel block 26 and the bridge 24 is a spring 28 normally tending to move the feeler towards its rearward feeling position. The parts so far described may be substantially the same as the similar parts shown and described more fully in the patent to Ed-

ward S. Stimpson, No. 1,309,226, dated July 8, 1919, to which reference may be had for further details of feeler mechanism.

The feeler 23 is held retracted by the detent 29 which may be variously constructed, but in the embodiment shown is in the form of a blade extending transversely of the feeler stem 25 and is pivotally mounted upon the bracket 30 by the pivot pin or screw 31. The detent 29 is constructed and arranged to engage notches 32 formed in the lower face of the feeler stem and the detent is rocked about its pivot 31 to the feeler engaging position by a coiled spring 33 mounted in the socket provided in the enlargement 34 upon the bracket 30, and one end of the detent or lever 29 enters a slot formed in the upper portion of the enlargement 34, whereas the opposite end of this detent or lever extends through a slot formed in a projection 35 extending frontwardly from the bracket 30 near one end of this bracket.

It is desirable that the detent supporting bracket 30 be mounted upon the feeler stand 21 for adjustment toward and from the front of the loom relatively to this stand, so that the detent may be adjusted to hold the feeler 23 retracted to different degrees. To this end in the construction shown, the bracket 30 is adjustably secured to the feeler stand 21 by providing the bracket with a rearwardly extending portion 36 which is slotted as at 37 and may be rigidly secured to the feeler stand 21 in the desired position of adjustment by a clamping bolt 38 extending through the slot 37. It is desirable that means be provided by which the bracket 30 may be accurately moved toward and from the feeler stand to the desired position of adjustment and then clamped in this position. To this end the bracket 30 is provided with an adjusting screw 39 the head portion of which is rotatably mounted in a notch 40 provided in an upwardly extending portion of the bracket 30, while the threaded end of this screw is screwed into a lug 41 formed upon the feeler stand 21. The arrangement is such that the adjusting nut 39 may be engaged by the fingers and rotated in one direction to move the bracket 30 towards the feeler stand and rotated in the opposite direction to adjust the bracket away from the feeler stand, and after the desired adjustment has been obtained, the parts are secured in this position by tightening the clamping bolt 38.

The detent supporting bracket 30 should be so adjusted that when the feeler 23 is pushed forwardly on a detecting beat by a substantial amount of filling on the filling carrier or bobbin 42, the detent 29 will engage one of the notches 32 and hold the feeler in its retracted position, but if the filling upon the filling carrier or bobbin has reached a nearly exhausted condition, then

the extent to which the feeler is moved forwardly upon a detecting beat should not be sufficient to engage the detent 29, whereupon the feeler will remain free to detect the condition of the filling on each detecting beat until a replenishment of filling is effected by the feeler and the chain of mechanism controlled thereby.

It is desirable that the detent 29 hold the feeler retracted in an inoperative position during the operation of a predetermined number of picks, say, for example, fifty picks, and then be actuated to release the feeler so that it may feel the condition of the filling in the shuttle upon one or two detecting beats and then again hold the feeler in its retracted position provided a substantial amount of filling is found to be present in the shuttle. Various means may be provided for releasing the feeler after it has been held idle a desired length of time, and in the present case this is accomplished by imparting movement to the detent from one of the gears commonly provided upon looms to rotate the usual take-up or sand roll. To this end the projection 35 above mentioned is provided with a vertical hole in which a plunger 43 is mounted to engage the under face of the detent lever 29, the arrangement being such that if the plunger 43 is forced upwardly it will rock the right-hand end of the lever 29 upwardly and depress the opposite or detent end of this lever to thereby release the feeler 23. The plunger 43 is actuated by a flexible wire 44 mounted within the sheath 45, one end of which sheath is secured to the under face of the projection 35, while the opposite end is secured to a lug 46 provided upon a bracket 47 which bracket is adjustably secured to a portion of the loom frame by a bolt 48.

Slidably mounted within the lug 46 and projecting therefrom is the plunger 49, and this plunger is actuated by a lever 50 which is pivotally mounted at 51 upon the bracket 47, and one face of the lever 50 rests against the outer end of the plunger 49. Rocking movement is imparted to the lever 50 by a projecting head 52 which may be secured to one of the spokes 53 of the gear 54, and this head engages a projection 55 upon the lever and rocks the lever in a left-hand direction as will be clear from Figs. 1 and 7. The amount of rocking movement imparted to the lever 50 is limited by a pin 56 projecting from the face of the bracket 47 and which pin lies within the space formed by the bifurcated end of the lever 50. If desired, the plungers 43 and 49 may consist simply of the projecting ends of the flexible wire 44, and it will be apparent that as the lever 50 is rocked in a left-hand direction it will force the plunger 49 inwardly and that this movement will be imparted to the plunger 43 through the wire 44 to actuate the

detent. The gear 54 is shown as one of a chain of gears, 57, 58 and 59, which actuate the usual take-up roll.

It may be desirable not only to hold the feeler in the frontmost position to which it is pushed by the filling upon a detecting beat, so that it will not strike the filling and be pushed forwardly thereby upon each detecting beat, but it may be desirable to impart an additional forward movement to the feeler so that the same will be held entirely out of contact with the filling in the shuttle for a desired period of time. Means to this end is shown in the modification shown in Figs. 5 and 6, and will now be described.

The bracket 60 of Fig. 5 for the most part may be similar to the bracket 30 of Figs. 1 to 4 inclusive, and may be secured to the feeler stand 21 in the manner above described. This bracket, however, differs from the bracket 30 in that it is constructed to support the detent or lever 61 so that the latter will rock in a forwardly inclined plane, as will be apparent from Fig. 5. The detent 61 is pivotally secured to the bracket 60 by a bolt or pin 62 and the feeler engaging end of the same is urged upwardly by a spring 63 which may be similar to the spring 33 above described.

The object in mounting the lever 61 so that it will swing in a forwardly inclined plane is to cause the detent to move forwardly as it enters one of the notches 32 of the feeler stem. Upon referring to Fig. 6 it will be seen that the detent will engage one of the notches 32 when its upper edge is in the position designated by the dotted line *a* and that when the detent is moved completely into engagement with a notch 32, its upper edge will occupy the position indicated by the line *b*, with the result that the feeler will have been moved forwardly the distance between the lines *a*—*b* after the feeler has been engaged by the detent. The feeler engaging portion of the lever 61 is bevelled off or reduced in thickness, as indicated by 64, so that this portion of the lever may enter a notch 32 and extend to the bottom of the notch. In the modification of Figs. 5 and 6, this upper end of the plunger 43 is bent laterally as shown to provide a wide surface that engages the lower edge of the inclined detent.

As the result of this construction, the feeler will be held in a position entirely out of reach of the filling upon the succeeding detecting beats. The detent 61 may be actuated to release the feeler 23 by the mechanism above described and the construction as shown in Figs. 5 and 6 operates substantially the same as in Figs. 1 to 4 inclusive, except that by mounting the detent to operate in the inclined position shown, it performs the additional function of moving the feeler

frontwardly beyond the forward position to which it is moved by the filling upon a detecting beat.

The lay 65 may be of usual construction and is provided with a shuttle box 66, the front wall 67 of which is provided with an opening 68 which, when the shuttle 69 is in the shuttle box, registers with a corresponding opening 70 formed in the front wall of the shuttle. The shuttle box and shuttle may be of the construction now commonly used in feeler looms, the essential being that a proper opening be provided for the entrance of the feeler into the shuttle to feel for the filling when the feeler is active on a detecting beat.

What is claimed is:

1. An intermittent feeler mechanism for looms, comprising, in combination, a feeler mounted to detect substantial exhaustion of the filling within a shuttle, a detent for engaging any one of a plurality of teeth on the feeler to hold the feeler in a retracted position and constructed and arranged to engage a tooth of the feeler when the latter is pushed frontwardly by a working supply of filling and operable to impart an additional frontward movement to the feeler to move it to an inoperative position, and means operable periodically upon the completion of a multiplicity of picks for releasing the feeler from the detent.

2. An intermittent feeler mechanism for looms, comprising, in combination, a feeler mounted to detect substantial exhaustion of the filling within a shuttle, a detent for holding the feeler in a retracted position and mounted to swing in a plane extending transversely to the axis of said feeler, means for moving the detent into holding engagement with the feeler when the latter is moved frontwardly by a working supply of filling and operable to impart an additional frontward movement to the feeler to move the latter to an inoperative position, and means operable periodically upon the completion of a multiplicity of picks for releasing the feeler from the detent.

3. An intermittent feeler mechanism for looms, comprising, in combination, a feeler mounted to detect substantial exhaustion of the filling within a shuttle, a detent for holding the feeler in a retracted position and constructed and arranged to engage the feeler when the latter is pushed frontwardly by a working supply of filling and operable to impart an additional frontward movement to the feeler to move it to an inoperative position, and a flexible controller for imparting movement from a power driven portion of the loom to the detent to free the feeler periodically.

4. An intermittent feeler mechanism for looms, comprising, in combination, a feeler mounted to detect substantial exhaustion of

the filling within a shuttle, a detent for holding the feeler in a retracted position and mounted to move in an inclined direction towards the front of the loom to engage the feeler when the latter is pushed frontwardly by a working supply of filling and operable to impart an additional frontward movement to the feeler to move it to an inoperative position, and means operable periodically upon the completion of a multiplicity of picks for releasing the feeler from the detent.

5. An intermittent feeler mechanism for looms comprising, in combination, a feeler mounted to detect substantial exhaustion of the filling within a shuttle, a detent for holding the feeler in a retracted position and mounted to swing frontwardly in an inclined direction to engage the feeler when the latter is pushed frontwardly by a working supply of filling and operable to impart an additional frontward movement to the feeler to move it to an inoperative position, and means for periodically actuating the detent to release the feeler.

6. An intermittent feeler mechanism for looms comprising, in combination, a feeler stand, a feeler mounted upon said stand to detect substantial exhaustion of the filling within a shuttle, a detent for holding the feeler in a retracted position when the feeler is pushed frontwardly by a working supply of filling, a bracket adjustably secured to the feeler stand to support the detent, an adjusting screw for adjusting the bracket toward and from the front of the loom, means for clamping the bracket to the feeler stand in its adjusted position, and means for periodically actuating the detent to release the feeler.

7. A feeler mechanism for looms comprising, in combination, a feeler stand, a feeler mounted upon said stand to detect substantial exhaustion of the filling within a shuttle, a detent for holding the feeler in a retracted position when the feeler is pushed frontwardly, a bracket adjustably secured to the feeler stand to support the detent, an adjusting screw for adjusting the bracket relative to the feeler stand to move the detent relative to the feeler, means for clamping the bracket to the feeler stand in its adjusted position, and means operable periodically upon the completion of a multiplicity of picks for releasing the feeler from the detent.

8. An intermittent feeler mechanism for looms comprising, in combination, a feeler mounted to detect substantial exhaustion of the filling within a shuttle, a detent for holding the feeler in a retracted position when the feeler is pushed frontwardly by a working supply of filling, and means operable periodically to release the feeler from the detent, comprising a plunger, a rocking le-

ver engaging an end of the plunger, a protruding head provided upon a power actuated element of the loom and movable into and out of engagement with said lever to 5 rock the latter and actuate the plunger, and means for imparting the movement of the plunger to the detent.

9. An intermittent feeler mechanism for looms comprising, in combination, a feeler 10 mounted to detect substantial exhaustion of the filling within a shuttle, a detent for holding the feeler in a retracted position when the feeler is pushed frontwardly by a working supply of filling, and means operable periodically to release the feeler from the 15 detent, comprising a plunger, a rocking lever having a limited swinging movement and engaging an end of said plunger, a protruding head provided upon a gear of the loom and positioned to engage and rock the lever 20 in a direction to force the plunger inwardly,

and means for imparting the movement of the plunger to the detent.

10. An intermittent feeler mechanism for looms comprising, in combination, a feeler 25 mounted to detect substantial exhaustion of the filling within a shuttle, a detent for holding the feeler in a retracted position when the feeler is pushed frontwardly by a working supply of filling, and means operable periodically to release the feeler from the 30 detent, comprising a plunger, a rocking lever that engages an end of the plunger, a protruding head provided upon a rotating element of the loom and positioned to engage and rock the lever to actuate the plunger, and a sheath-enclosed wire for imparting the movement of the plunger to the detent to release the feeler. 35

In testimony whereof, I have signed my 40 name to this specification.

EDWARD S. STIMPSON.
